DATA COLLECTION COMPONENT

James W. Kelso, Los Angeles County, Calif., assignor to
MSI Data Corporation, Montclair, Calif.

Filed Dec. 2, 1970, Ser. No. 26,250

Term of patent 14 years

Int. Cl. D14—02

U.S. Cl. D26—5

FIG. 1 is a front perspective view of the data collection component showing my new design;

FIG. 2 is a right-hand end view of the data collection component as illustrated in FIG. 1; and

FIG. 3 is a rear elevational view of the data collection component as illustrated in FIG. 1.

The side of the data collection component opposite to the side shown in FIG. 2 is plain, unornamented and similar to the illustrated side.

I claim:

The ornamental design for a data collection component, as shown and described.
